UNITED STATES PATENT OFFICE.

THOMAS D. CRAIG, OF LOS ANGELES, CALIFORNIA.

MANDREL.

Application filed October 31, 1927. Serial No. 230,010.

My invention relates generally to mandrels and more specifically to a mandrel particularly adapted, although not necessarily, for use in dentistry, in supporting a disk of abrasive material, the mandrel being insertable into the chuck of the hand piece of a dental engine for clamping thereof by the chuck, so that when the engine is in operation, the mandrel and disk will be rotated to thereby permit grinding operations to be performed on the teeth; all of which is well known in the art and will be understood.

A well known form of mandrel of the above described character comprises a pair of telescopically associated members in which the inner member is in the form of a pin insertable into the outer member constituting a sleeve, the members having co-acting heads adapted to engage opposite sides of a disk through the center of which the pin extends, to the end that the disk will be supported on the mandrel at right angles to the axis of the latter. For the purpose of retaining the pin against displacement from the sleeve it is bent or undulated longitudinally, and reliance is placed on the frictional engagement of the undulations with the inner wall of the sleeve to retain the pin in the latter. It has been found in practice that this method of retaining the pin is extremely unreliable and that the pin frequently loosens and works out of the sleeve during the grinding operation, thus causing loss of time as well as subjecting the patient to the danger of injury by the disk.

It is a purpose of my invention to provide a mandrel which embodies extremely simple means responsive to clamping of the mandrel in the clutch of the hand piece to cause the inner member of the mandrel to be positively retained against displacement from the outer member and the inner member to be firmly supported so as to insure the true and even running of the disk, thus greatly facilitating the work of the dentist and entirely eliminating the danger of injury to the patient as a result of displacement of the inner member.

I will describe only one form of mandrel embodying my invention and will then point out the novel features in claim.

In the accompanying drawing

Fig. 1 is a view showing in side elevation one form of mandrel embodying my invention, applied to the hand piece of a dental engine;

Fig. 2 is an enlarged vertical sectional view taken on line 2—2 of Fig. 1 and looking in the direction of the arrows; and

Fig. 3 is an enlarged sectional view taken on the line 3—3 of Fig. 1 and looking in the direction of the arrows.

Referring specifically to the drawing in which similar reference characters designate similar parts in each of the several views, my invention in its present embodiment comprises a pair of members designated generally at M and M', and capable of being telescopically associated with each other, the former being in the form of a sleeve 10 and of uniform diameter and enlarged at one end to provide a circular head 11 having a plurality of prongs 11^a projecting from the outer side thereof, while the latter member is in the form of a pin 12 of such diameter as to have a sliding fit within the sleeve so as to permit its being readily unserted or withdrawn, the pin 12 being provided with a circular head 13. The mandrel as above described is adapted to support a disk 15 of abrasive material such as sandpaper, provided with a central opening through which the pin 12 is adapted to be extended. With the disk placed on the pin, the latter is inserted into the sleeve until the disk is clamped between the heads 11 and 13, at which time the prongs 11^a will pierce the disk and thus lock the disk to the sleeve for rotary movement therewith.

The mandrel with the disk 15 supported thereon is adapted to be inserted into the jaws 16 of the clutch 17 of a conventional form of hand piece 18 constituting part of a dental engine (not shown) such as is commonly used in dental laboratories to provide the necessary power for driving various forms of tools clamped in the chuck 17. The jaws 16 are adapted to be contracted to clampingly engage the sleeve 10 by means of a contracting element 19 mounted in the housing 20 of the hand piece 18 and bearing against the tapered upper end of the jaws, the element co-operating with the tapered lower end of the housing 20 bearing against the similarly tapered lower end of the jaws, to contract the latter from both ends as the element is forced downwardly by a manually operable feed screw 21, all of which is conventional and will be understood.

For the purpose of retaining the pin 12 against displacement from the sleeve 10 when the latter is clamped in the jaws 16, the sleeve

is preferably rendered constrictable, and to this end, the wall of the sleeve, in the present instance, is provided with longitudinally extending and diametrically opposite slots 22, 5 the slots being spaced from the ends of the sleeve and providing therebetween, flexible portions 23. It will be clear that when the jaws 16 are contracted to clampingly engage the sleeve they will simultaneously constrict 10 the portions 23, thus flexing the latter inwardly into clamping engagement with the pin 12, so that the pin will be firmly gripped in the sleeve against displacement therefrom. The clamping action of the chuck is thus 15 caused to perform the dual function of preventing displacement of both the sleeve and the pin from the chuck. Furthermore as the pin is firmly supported axially within the sleeve, the true and even running of the disk 20 is insured at all times, thus greatly facilitating the work of the dentist.

Although I have herein shown and described only one form of mandrel embodying

my invention, it is to be understood that various changes and modifications may be made 25 therein without departing from the spirit of the invention and the spirit and scope of the appended claim.

I claim as my invention:

A mandrel comprising a pair of tele- 30 scopically associated members adapted to co-operate in supporting an abrasive element, the wall of the outer member being slotted longitudinally at circumferentially spaced points to provide portions capable of being flexed inwardly in response to the constricting action of a clutch upon said portions so as to engage and grip the inner member and thereby prevent displacement of the latter from the outer member, the slots terminating in spaced relation to both ends of the outer member so that the wall of the outer member at its ends remains unbroken and rigid to insure that the mandrel will be rigidly supported centrally in the chuck.

THOMAS D. CRAIG.
